UNITED STATES PATENT OFFICE.

HORACE MANN, OF MUSKEGON, MICHIGAN.

AUTOMATIC LOCOMOTIVE-BOILER-COMPOUND FEEDER.

1,193,038.

Specification of Letters Patent.

Patented Aug. 1, 1916.

Application filed March 25, 1915. Serial No. 16,994.

To all whom it may concern:

Be it known that I, HORACE MANN, a citizen of the United States of America, residing at Muskegon, in the county of Muskegon and State of Michigan, have invented certain new and useful Improvements in Automatic Locomotive-Boiler-Compound Feeders; and I do hereby declare the following to be a full, clear, and exact description 10 of the invention, such as will enable others skilled in the art to which it appertains to make and use the same.

This invention relates to an automatic boiler compound feeder adapted to be interposed in the feed pipe leading from the injector to the boiler of a locomotive.

The invention is especially adapted for use with railroad locomotive boilers and includes constructions and arrangements of 20 parts permitting the automatic feed of a boiler compound in solution to the interior of a boiler as water is injected into the boiler.

An object and purpose of my invention is 25 to provide in a device of this character, a very simple yet efficient construction and in which valves and other like adjustable parts are practically eliminated so as to require little or no attention.

30 Other objects and purposes consisting in novel constructions and functions of parts will be apparent as understanding is had of the embodiment disclosed in the accompanying drawing, in which;

35 Figure 1 is a vertical section taken lengthwise of the device. Fig. 2 is an end view thereof; and Fig. 3 is a horizontal section on the line 3—3 of Fig. 2.

Like reference characters refer to like 40 parts throughout the several views of the drawing.

The boiler feed pipe leading from the injector to the boiler is indicated at 1. The device comprising my invention is interposed in the length of this pipe and includes a sleeve 2, into the ends of which the ends of pipes 1 are threaded, and a chamber 3 above the sleeve, a partition 4 dividing the chamber from the sleeve as shown. This 45 chamber is adapted to receive and contain any suitable boiler compound used for the purpose of dissolving scale already formed and preventing deposit of scale thereafter on the various surfaces in the boiler. The compound is introduced through an opening in 50 the top of the chamber which may be closed

by any suitable cover 5 retained in place by the member 6 as shown.

A short conical tube 7 having a slightly larger diameter at its free end than at the 60 other is connected to an elbow 8 which is secured to a pipe 9 passing vertically through the partition 4. By means of suitable connections 10 pipe 9 is attached to the curved pipe 11 projecting upwardly into the chamber 65 3 and then turned back upon itself, with its lower end passing through and connecting with the top of a box 12 cast integral with the partition 4. The sides of this box are perforated at a plurality of places as 70 shown at 13.

A vertical tube 14 is positioned a short distance from the curved pipe 11. Adjacent its lower end it is secured, through suitable connections 15, to a pipe 16 passing 75 through the partition 4. A T-coupling or equivalent device 17 is secured to the lower end of pipe 16 and has a short tubular section 18 threaded into one end. In its other end a funnel shaped member 19 is secured 80 in place, the larger end of said member being presented toward the flow of water through sleeve 2, while at its other end it is formed into a tube 20 of comparatively small diameter, extending into the part 18. 85 The tube 14 heretofore described, at its upper end is provided with a cap 21 which may be adjusted on the tube in any suitable manner so as to vary the size of the passages into said tube through the openings 22 and 23 in 90 the tube and cap respectively to thereby control the amount of solution of boiler compound passing into the pipe.

In practice the chamber 3 is partially filled with a soluble boiler compound. When no 95 water is passing through the feed pipe into the boiler no action takes place but during the time that the injector is working and water is passing through the pipe, the boiler compound is introduced into the boiler. Water 100 passing through pipes 1 and sleeve 2 in the direction indicated by the arrow A flows at a high speed and a part of it entering the tube 7 is carried through the curved tube 11 into the box 12 being forced through the 105 openings 13. The water forced through the openings agitates the boiler compound and dissolves a portion of it filling the chamber 3. The solution thereupon passes through openings 22 and 23 into the tube 14 and 110 down into the member 17. Part of the feed water will also enter the enlarged end of

member 19 and be forced through the restricted rear end 20 at a very high rate of speed carrying with it any liquid that may be in the members 17 and 18. In this manner 5 the solution of boiler compound is introduced into the water on its way to the boiler and any back pressure which might tend to prevent the flow of the solution of boiler compound out of the chamber 3 is overcome 10 and eliminated by the increased velocity given to the water as it leaves the member 19 through the restricted end 20.

It will be apparent from this construction 15 that I have provided a simple and economically manufactured device which may be interposed in the length of the feed pipe to a locomotive boiler. It will also be apparent that the locomotive boiler compound is introduced uniformly with the flow of water 20 into the boiler and that no introduction of the compound will take place except as water is injected into the boiler. Furthermore this construction contains no parts liable to 25 get out of order such as valves or the like and is fully capable of withstanding the severe conditions under which it will be subjected on locomotive boilers.

I claim:—

1. In combination, a chamber adapted to 30 contain a boiler compound, a sleeve below said chamber with a partition between the chamber and sleeve, a perforated box in the lower part of the chamber, a curved conduit tube leading into the box at one end, passing 35 through the partition and at its other end turned substantially parallel to the sleeve, a second conduit tube in the chamber passing through the partition, an adjusting device at the upper end of said tube, a tubular connection to the lower end thereof lying substantially parallel to the sleeve, and a funnel 40 member inserted in and filling one end of the said connection, the reduced end of said member extending past the lower end of the 45 conduit tube.

2. In combination, a sleeve adapted to be interposed in the feed pipe to a locomotive boiler, a chamber adapted to contain boiler compound connected with the sleeve, a perforated box in the chamber, means leading 50 from the box to the sleeve whereby water passing through the sleeve is partially deflected and carried to the box, a conduit tube

to carry said water back to the sleeve, a tubular connection at the lower end thereof lying 55 substantially parallel to the sleeve, and a funnel member in said connection having its large end open to receive a part of the water flowing through the sleeve, and its reduced end extended past the lower end of said conduit tube.

3. In combination, a chamber adapted to contain boiler compound, a sleeve formed integrally with the chamber adapted to be interposed in the feed pipe to a locomotive 60 boiler, a perforated box in the chamber normally covered by the boiler compound in the chamber, means to force a portion of the water passing through the feed pipe into the box and through the perforations thereof to 65 thereby agitate and dissolve a portion of the boiler compound in the chamber, and means to carry the said water and compound in solution back into the sleeve, said means comprising a pipe extending from the chamber 70 into the sleeve and a device secured at the lower end of said pipe positioned lengthwise of the sleeve through which a portion of the water in the feed pipe passes to create a suction to draw the boiler compound in solution 75 from the chamber.

4. In combination, a chamber adapted to contain a boiler compound, a sleeve below the chamber with a partition between the chamber and sleeve, said sleeve adapted to be interposed in the feed pipe to a locomotive 80 boiler, a perforated box in the lower part of the chamber, a conduit in the chamber leading at one end into the box and at the other end through the partition, an extension to 85 said conduit in the sleeve turned parallel to the sleeve and open in the direction from which the water flows in the feed pipe, a second conduit in the chamber through which the contents of the chamber may escape to 90 the sleeve, the lower end of said conduit passing through the partition, and means to create a suction at the lower end of said conduit within the sleeve, substantially as described. 95

In testimony whereof I affix my signature in presence of two witnesses.

HORACE MANN.
